TOY TRUCK TRACTOR

Gary B. Smart, 3500 Carter Road,
Portsmouth, Va. 23703

Filed Oct. 31, 1972, Ser. No. 302,407

Term of patent 14 years

Int. Cl. D21—01
U.S. Cl. D34—15 AJ

FIG. 1

FIG. 2

FIG. 3

FIG. 4

FIG. 1 is a top plan view of a toy truck tractor showing my new design;

FIG. 2 is a front elevational view thereof;

FIG. 3 is a rear elevational view thereof;

FIG. 4 is a right side elevational view thereof, the left side being a mirror image thereto.

I claim:

The ornamental design for a toy truck tractor, as shown and described.
